UNITED STATES PATENT OFFICE.

LAURA E. TYGERT, OF ALBANY, NEW YORK.

COOKING-STAND FOR PRESERVING-CANS.

SPECIFICATION forming part of Letters Patent No. 578,375, dated March 9, 1897.

Application filed July 22, 1896. Serial No. 600,114. (No model.)

To all whom it may concern:

Be it known that I, LAURA E. TYGERT, a citizen of the United States, residing at Albany, in the county of Albany and State of New York, have invented certain new and useful Improvements in Cooking-Stands for Preserving-Cans, of which the following is a specification.

My invention relates to improvements in cooking-stands for use for holding preserving-cans for cooking their contents when preserving or canning fruits, vegetables, &c.; and it consists in the devices and elements and combinations of devices and elements set forth and described in this specification; and the objects of my improvements are, first, to provide a simple means for securely holding one or more canning-jars or other vessels in place in a cooking-kettle while cooking the contents of the jars and for facilitating the removal of the same from the cooking-kettle without least liability of the operator being scalded or burned; also, providing means by which cans of different sizes may at will be retained in place and be removed at the same time, and, further, to provide means by which two or more cans or jars may be simultaneously seated in holding devices and held in place therein in the cooking-stand and be under the control of the operator and by her be simultaneously removed from the cooking-kettle and carried to a place of deposit without least danger of scalding or giving discomfort to the operator. I attain these objects by the means illustrated in the accompanying drawings, forming a part of this specification, in which—

Figure 1 is a plan view of a cooking-stand embodying the improvements in my invention. Fig. 2 is a side elevation of the same. Fig. 3 is a section view of the lower-end holder, and Fig. 4 is a section view of the upper-end holder.

The same letters of reference refer to similar parts throughout the several views.

In the drawings, A represents the lower-end-holding device for receiving and holding in place a can or jar when its contents are to be cooked by the action of heat from boiling water contained within a cooking-kettle or other vessel.

B is the handle, and C is the upper-end-retaining piece or device.

The lower-end-holding piece A comprises one or more bottom-receiving portions, as *a* and *b*, suitably connected with a ring-form web *c*. The bottom-receiving portion *b* may be comprised by two or more downwardly-projected and inwardly-turned holding-lips *b* *b*, formed, preferably, integral with the web *c*, as shown by full lines in Fig. 3, or upwardly-projected posts *a* *a*, preferably integral with said web *c*, as shown in said Fig. 3. The downwardly-projected holding-lips *b* *b* are connected with the web *c* with their upper ends set at a line corresponding with the circumferential line of the jar or can seating therewith, and they may be made with bearing-surfaces of angular form when the side walls of the can or jar, at the bottom thereof, are at right angles with the bottom of the same, yet when the bottom corner of the can or jar is curved in form I would form the said holding-lips *b* *b* with concave curves on their inner sides, as shown in Fig. 3, so as to correspond with the rounded bottom corners of the can or jar. The upwardly-projected posts *a* *a* are also preferably integral with web *c*, and are employed in number of two or more set on a circular line corresponding with the circumferential line of a can or jar of larger diameter than one to be seated and supported from the downwardly-projected bottom-receiving portions *a* above described. When the bottom corners of the can or jar are rounded, the inner sides of said posts are made with concave surfaces, as shown, so that these posts *a* *a* may present to the bottom portion of the can or jar a form or shape of holding-surface which will readily receive said bottom portion and retain the same from shifting in either direction in relation to the holding device.

If preferred, in some cases there may be employed in lieu of the two or more downwardly-projected holding-lips *b* *b* a circular or ring-form holding device, as *b'*, (shown and indicated by full and by dotted lines in Fig. 3,) which ring-form holding device may be substantially continuous and integral with the web *c* and be annular to a central opening *a'*, Fig. 3; and have its inner side concave and so

shaped as to receive and retain the bottom portion of the can or jar; and, if preferred, the upwardly-projected can-retaining pieces, comprising two or more upwardly-projected posts 5 *a a*, may be formed so as to consist of a continuous ring-form device, as *a'*, (shown by full lines and dotted lines in Fig. 3,) which ring-form portion is made, preferably, integral with the web *c* and with a form of inner surface 10 corresponding with the bottom corner portion of the can or jar, so as to retain the same in place from shifting in any direction. When this lower-end-retaining device is provided with the bottom-retaining devices *a a* or *a'* 15 and *b b* or *b'*, integral with the web *c*, the said device *A* will be adapted to receive and retain in place cans of different diameters at their bottoms, so that with a single cooking-stand jars or cans of capacity of quarts or 20 pints may be properly held in place while their contents are being cooked.

Although the stand may comprise but one lower-end-holding device *A*, yet I prefer to employ two or more of said devices *A*, as shown 25 in Figs. 1 and 2, in which case I would arrange the handle *B* relatively central and would make the web *c* of each device integral with the web or webs of the others in the group of holding devices *A* preferred to be 30 joined together in a single stand, as illustrated in Fig. 1.

The handle *B*, I prefer to make in the form of a vertical rod, as *d*, secured by any suitable means, and preferably by a screw-nut *d'*, 35 with the web portion *c*, and for convenience of carrying this stand I provide the cross-piece *d'*, suitably secured to the upper end of the vertical rod *d*, as shown.

The upper-end-retaining device *C* consists 40 of a suitable metal piece carrying two or more downwardly-projected holding-lips *e e*, set relatively on a circular line corresponding with the circumferential line of the outer side (or inner side) of the neck or mouth of the can or jar. For convenience and use with cans 45 or jars having their upper ends or necks or mouths of different diameters I provide a second series of two or more projections, as downwardly-projected lips *e' e'*, set relatively on a circular line corresponding with one of larger 50 diameter than on which lips *e e* are set. These holding-lips *e e* and *e' e'* are preferably integral with the crescent-shaped web *e²*, although the web employed may be of circular form 55 and continuous, if preferred, yet made in the form of a section of a circular piece or crescent-shaped it answers all the purposes and saves metal. This upper-end-retaining piece *C* is provided with ear *e³*, made integral with 60 web *e²* and having perforation *e⁴* for receiving a supporting or retaining rod *D*, which is secured in place with the web *c* of the lower-end-retaining device *A*, with which this upper-end-retaining device *C* is to be employed. 65 This retaining-rod *D* is vertical and parallel with the vertical rod *d* of the handle *B* and

is so arranged in relation to the center of the webs *c* and *e²* that when the web *e²* of this upper-end-retaining piece is in place holding with the upper end portion of a can 70 or jar its center will be coincident with the center of web *c* of the lower-end-retaining device *A*. This upper-end-retaining piece *C* is by its perforation *e⁴* free to be moved vertically at will in either direction, so as to 75 be readily adjusted to the height of the can or jar the piece *C* is to hold with by its holding devices *e e* or *e' e'*. The said retaining-piece *C* may be swung to one side and relatively off from the lower-end-retaining device 80 *A* or be raised off from its retaining-shaft *D*, as may be preferred, to be replaced thereon when a can is to be seated in the holding device *A* and retained therein. When the stand is to comprise two or more lower-end-retaining devices, as *A A*, I provide with each said device a retaining-rod *D* and upper-end-retaining device *C*, as described, so that each can in the stand may be provided with suitable holding devices, as *e e* or *e' e'*, for engaging 85 with cans of varying sizes, as may be required. Although these upper-end-retaining devices, when used two or more in a stand, may each be separate and independent pieces, yet, if preferred, they may be made to be integral with each other and be made to work on the handle-rod *d* as a retaining-rod by being perforated at a point midway between the centers of the two or more of said upper-end-retaining devices in the group, and as indicated by dotted lines in Fig. 2, in which case 90 the rods *D* will be dispensed with, the vertical rod *d* of the handle *B* serving the purpose of a retaining-rod.

When this stand is to be used, the operator 105 will place the can or jar (if but one device *A* comprises the stand) or cans and jars, containing the substances to be cooked, will be seated in their respective places with their bottom portions on the devices *a* or *b* or *a'* or *b'*, accordingly as may be provided and as may be in correspondence with the diameters of the bottoms of the respective cans or jars, when the upper-end-retaining pieces will be moved to position to bring the respective holding devices *e e* or *e' e'*, as may be required, into engagement with the upper end portions of the respective cans. When the can or jar or cans or jars are so placed and secured, the operator will place this stand with its contents on 110 the bottom of a suitable cooking kettle or vessel *F*, containing an inch or more of water, or enough to submerge the lower ends of the cans to a suitable distance, and will submit the cans and their contents to the action of the 115 boiling water in the cooking vessel for such a length of time as may be preferred or be necessary to properly cook the contents of the can or jar. The operator will then by the handle *B* remove the stand and the jars or cans thereon from the cooking vessel and remove the heated cans or jars from the stand 120 125 130

and replace them by other cans or jars containing substances to be cooked, when the stand will be again placed within the cooking-kettle for submitting the contents to the action of the heated water, as before, and all operations with cans or jars when canning fruits or vegetables may be carried on in a cleanly manner and without liability of the operator being scalded by either hot water or steam and also without the least discomfort from heat.

This stand may be employed for holding vessels containing eggs required to be cooked by poaching process and for boiling or cooking gravies or farinaceous substances, as oatmeal or flour or meal of wheat or other grains.

This stand may be constructed of any suitable metal, cast or struck, and its parts may be made with any suitable forms as may be suitable to adapt them for use with cans, jars, or other vessels of sizes and forms as may be found to be advantageous for use.

When downwardly-projected holding-lips $b\ b$ are employed for engaging with the lower or bottom end of the jar or can or other vessel for holding such vessel from shifting, the water within the cooking vessel will readily have contact with the bottom and side walls of the can or jar to the distance it is submerged, as the water may freely flow through the openings between said lips, while when the circular concave form of holding device, as b' , Fig. 3, is employed the notches or ports b^2 provided in such devices (indicated by dotted lines in Fig. 3) will allow the water in the cooking vessel to readily flow to a contact with the bottom or lower portion of the side walls of the jar or vessel.

Having described my invention, what I claim, and desire to secure by Letters Patent, is—

1. In a cooking-stand the combination with device A, described, adapted to retain the lower end of a can, jar or other vessel in place from shifting, of a handle adapted to serve as a means for transferring the stand to or from a cooking vessel, substantially as and for the purposes set forth.

2. In a cooking-stand the combination with an encircling web provided with devices described for retaining the lower ends, or bottom portions of two cans, jars, or other vessels, each of different diameter in place when respectively seated in their retaining devices, and a handle adapted to serve as a means for transferring the stand to or from a cooking vessel substantially as and for the purposes set forth.

3. In a cooking-stand, the combination, with device A described, adapted to hold in place cans, jars or other vessels, of two different sizes, one at a time, by their respective lower end portions, an upper-end-retaining device and a retaining-rod between device A, and said upper-end-retaining device, of a handle adapted to serve as a means for transferring the stand to or from a cooking vessel, substantially as and for the purposes set forth.

4. In a cooking-stand, the combination with a lower-end-retaining device A comprising web c and downwardly-projected holding-lips $b\ b$ and a handle, of an upper-end-retaining device substantially as and for the purposes set forth.

5. In a cooking-stand for holding cans, jars or other vessels, the combination of a lower-end-holding device comprising web c , downwardly-projected holding-lips $b\ b$ set on a circular line of one given diameter, and upwardly-projected retaining-posts $a\ a$ set on a circular line of a different diameter, of a handle for transfer of said stand with can, jar or other vessel therein, to or from a cooking vessel, substantially as and for the purposes set forth.

6. In a cooking-stand, the combination with device A described adapted to hold a can, jar or other vessel in place by its lower end portion, of an upper-end-retaining device C provided with two or more downwardly-projected holding-lips adapted to engage with the upper end portions of the supported vessels, of like or different diameters, a retaining-rod fixed with device A, and holding with device C and adapted to allow the latter to be placed or displaced at will, and a handle adapted to serve as a means for transferring the stand to or from a cooking vessel, substantially as and for the purposes set forth.

7. In a cooking-stand, for holding cans, jars, or other vessels the combination of two or more lower-end-holding devices A, described, a corresponding number of upper-end-retaining devices C, described, one or more retaining-rods secured to devices A and adapted to be placed at will into engagement with the upper ends of the vessels, and a handle adapted to serve as a means for transferring the cooking-stand to or from a cooking vessel, substantially as and for the purposes set forth.

LAURA E. TYGERT.
